AIRPLANE

Hans Mascow, Neisse, Upper Silesia, Germany

Application January 15, 1932, Serial No. 587,035,
and in Germany June 29, 1931

3 Claims. (Cl. 244—17)

This invention relates to an ornithopter enabling, without great expenditure of force, remarkably longer aviating than done by conventional airplanes in use hitherto, and, in case of 5 not too adverse atmospheric conditions in fact continuous aviating even without any upcurrents, above all things taking advantage only of the forces of gravity and of the currents of air, produced by any relative forward motion, 10 whether gliding or soaring or only currents of air, and operating on the aerofoils.

The construction of ornithopters or airplanes with flapping aerofoils has been done hitherto on the supposition that the greatest lifting effect 15 possible and also a greater propelling power had to be produced by means of the wings, the result of which were apparatus where a large amount of the effect produced was lost by friction in the mechanism and as internal stress in the rods, 20 a direct lifting effect being impossible.

In contrast to the conventional method the oscillating wings of my novel ornithopter are arranged and actuated in such a way that by 25 each downward oscillation a direct lifting effect is effectuated on the joint and consequently on the apparatus, after the manner of a see-saw, one end of which, when discharged, moves upward, the other end being put under accordingly greater weight, in the manner of a doubled- 30 armed lever. The result is that 100 per cent of the exertion made is utilized and that only the downward oscillation is effectuated by pedal force whereas the raising is done automatically by the pressure of the air from below. During 35 the oscillation and after all during the whole flight, just as in the case of any glider or airplane it is the force of gravity which chiefly effectuates the forward motion. This propulsion can be augmented by a suitable elastic or dif- 40 ferent construction of the planes. As a matter of course additional planes rigidly or elastically mounted and suitably arranged will prevent the immediate recoiling down of the airplane owing to the downward motion of the oscillating wings 45 after each lift. In my invention the vertical movement of the aerofoils is effectuated automatically by the surplus of the bottom pressure during each relative forward motion. During 50 the flight the wings can also be totally steadied in the way generally known.

In the following specification and accompanying drawing my invention will be more fully described and particularly pointed out.

In the drawing, Figure 1 is an oblique bottom 55 plan view of an airplane of the socalled duck-

type with front control provided with an embodiment of my invention.

Figure 2 is a summary transverse sectional view of the same type showing the novel arrangement 60 of power means.

Figure 3 illustrates the application of my invention to a downright parasol type.

Figure 4 designates a top plan view of the type above illustrated.

In all of the views, like parts are designated 65 by the same reference characters.

The body 2 with the struts 1 and the joint of struts 3 form the rigid frame of the airplane.

To the outer sides of the frame are secured 70 the rigid planes 4, which is novel too, either totally immovable to the struts 1 and the joint of struts 3 or in a better way, according to my invention, by inserting the extension—pieces 13 of their struts through the joints of the struts 3 and by elastically mounting them therein, thus 75 resting them in the pivot and between rubber buffers 11 or equivalent elastic matter. The result of mounting the trailing end of the strut more elastically than the front end of the strut is a greater oscillation and an augmented aero- 80 dynamic effect. It is to these inserted struts or in simple apparatus immediately to the joint of the struts that the inner parts of the planes, the socalled wings 5, are flexibly secured by 85 means of the joints 6. To these wings are secured treadles 7 extending inwardly into the interior of the body through lateral slits in the body 15 (in Figure 1) where they can be moved downwardly by the feet.

The wings are constructed in such a way that 90 especially in the zone of greatest amplitude of oscillation close to the treadles they are in their rear part elastically flexible upwards, a device from which additional propelling power results. It will be even more suitable to make them pass 95 into the shape of slotted wings or into two or several planes of the shape of a sun-blind elastically opening upward in consequence of the downward stroke of the wing. If the wings 5, as is supposed in my illustration, are not coupled together in the center, but if each of them will be separately actuated by one foot, the vertical steering (stabilizing) can be effectuated by them likewise.

By means of springs 8 the wings are secured to 100 the body in such a way that during a normal gliding they are in unstable equipoise, supported by a slight pressure of the foot.

The effect of the forces is as follows: During 110 the gliding or aviating or with a suitable current

of air the resulting buoyancy of the air (R) is actuating, forming, as it were, the end-bearings of the plane. If the aforesaid equipoise is interrupted by transferring the weight of the human body away from the seat to the treadles the part of the wing connected with the treadles is forced downward and the part close to the joints is drawn in an upwardly direction thus lifting the apparatus. The outer planes 4 now actuate as safety catches preventing an immediate recoil, whereas the continuous bottom pressure of the air effectuates an immediate raising of the wings as soon as the pressure of the foot is removed. Owing to the elastic mounting of the outer planes each downward stroke of the wings causes a slight elastic oscillation of the former.

The general construction of the airplane as well as of the planes particularly can be carried out in every way conventionally in use. Without detracting anything from the advantages of the invention or of the claims appended hereto it is to be understood that divergencies and different constructions are possible as for instance in

downright parasol planes as illustrated in Figure 3 or in the type of a tailless airplane or in biplanes. Moreover several couples of struts braced together or supported by means of stays can be arranged; even simple types without a body can be constructed with the embodiment of my invention.

I claim:

1. An engineless airplane comprising a body and inner and outer wings, means extending from said body for supporting said outer wings adjacent their inner ends, the outer ends of said inner wings being flexibly connected to the inner ends of the outer wings and the inner ends of the inner wings being adapted to be actuated downwardly by the feet of a pilot.

2. A device as set forth in claim 1 including springs for connecting the inner ends of said inner wings to said body.

3. A device as set forth in claim 1 including lateral slits in said body through which the inner ends of said inner wings extend.

HANS MASCOW.
